UNITED STATES PATENT OFFICE.

HILMER F. RODLER, OF DAVENPORT, IOWA, ASSIGNOR TO CALVIN J. MUMMERT, OF WEST NEW YORK, NEW JERSEY.

DESIGN FOR AN OIL-BURNER COVER.

Application filed May 14, 1926. Serial No. 17,726. Term of patent 14 years.

To all whom it may concern:

Be it known that I, HILMER F. RODLER, a citizen of the United States, residing at Davenport, in the county of Scott and State of Iowa, have invented a new, original, and ornamental Design for an Oil-Burner Cover, of which the following is a specification, reference being made to the drawing, forming a part hereof.

The annexed drawing is a view in perspective of my new oil burner cover.

I claim:

The ornamental design for oil burner cover substantially as shown.

HILMER F. RODLER.
